UNITED STATES PATENT OFFICE.

EDWIN NORTON, OF HAMILTON, BERMUDA, ASSIGNOR TO PERFECT VACUUM CANNING COMPANY, A CORPORATION OF MAINE.

VACUUM-CAN.

1,133,999.

Specification of Letters Patent.

Patented Mar. 30, 1915.

Application filed May 9, 1912. Serial No. 696,181.

To all whom it may concern:

Be it known that I, EDWIN NORTON, a citizen of the United States, residing at Hamilton, Bermuda, have invented certain new and useful Improvements in Vacuum-Cans, of which the following is a description, reference being had to the accompanying drawing and to the figures of reference marked thereon.

10 The invention relates to new and useful improvements in vacuum cans, that is, cans which are vacuumized after the cover is placed thereon and then sealed.

15 An object of the invention is to provide a can which may be cheaply made without sacrificing in any way the strength or efficiency of the can.

20 In the drawing, which shows by way of illustration one embodiment of the invention,—Figure 1 is a sectional view through the upper part of a can with my improvements applied thereto; Fig. 2 is a plan view of the same; and Fig. 3 is an enlarged detail of the center portion of the can, 25 showing the same partly in perspective and partly in section.

25 In carrying out my invention, I have provided a can construction wherein the can body and the cover may be made of un- 30 coated or black steel. By this I mean steel which is rolled into thin sheets such as are used in making tin plate. The surface of the steel which is to form the inside of the can is coated with a resisting coating such as 35 aluminum, lacquer or the like, and the outer surface of the metal is either left in its un- 40 coated oxidized state, or covered with a sizing varnish. The cover is provided with the usual perforation, through which the air 45 is exhausted from the can during the vacuumizing process.

50 In order that solder may be secured to the cover adjacent the perforation, which may be used for closing the said perforation after the air is exhausted in the can, I have treated the outer surface of the can adjacent the perforation so as to form a surface to which the solder will adhere. This treatment consists in grinding or cutting away the outer or oxidized surface of the cover adjacent the opening, and this 55 clean unoxidized surface will adhere to the solder.

55 Referring more in detail to the drawing, the can consists of a body portion 1 which

is formed from the uncoated or black steel referred to. The inner surface of this can body is coated with aluminum or lacquer, or some other similar substance. The cover 2 is, as herein shown, hermetically secured to the can body by rolling the outer edge thereof into a double seam 3, which is the well known construction, and will not need further description. A suitable sealing substance is rolled into the seam in the usual well known manner.

60 The outer faces of the can body and cover are in their ordinary oxidized or uncoated state, and may if desired be coated with a sizing or varnish. The cover is provided centrally thereof with a perforation, and around said perforation is an annular depression 5. The bottom of the depression 65 is ground, or otherwise treated, so as to remove the oxidized outer surface of the 70 metal, and to leave a clean bright surface. This surface will adhere to the solder. The depression in the can cover is substantially 75 filled with solder 6, as indicated in Fig. 1, and the perforation through the cover is 80 preferably made after the solder is applied, so that the perforation extends through the solder.

85 After the can is filled and the cover secured thereto, the air is exhausted from the can through the perforation, and the solder is then melted by a suitable iron and the perforation closed. The entire can may 90 then be dipped in lacquer or enamel, or otherwise treated, if desired, to give there- 95 to a protective coating.

95 From the above description, it will be apparent that I have provided a can wherein the metal used in the construction is the ordinary black sheet steel, without the usual tin coating, and these metal sheets may be very cheaply made and thereby the cost of the can greatly reduced. While I have shown the cover as having a central depression and the solder filling the same, it will 100 be obvious that the opening may be otherwise located and the construction varied, the essential feature being the removing of the outer oxidized surface of the black steel cover, so that the solder may be caused to 105 adhere thereto.

110 Throughout the claims, I have referred to the metal used in the construction of the can as "black steel," it being understood that this term is used to designate flat sheets

of steel which are not coated with tin or other metal as is usual in the construction of cans. While I have also referred to the depression as surrounding the perforation, it 5 will be understood that in the construction of the can the depression is first made, and after the solder is applied thereto, the perforation is then formed through the solder and cover.

10 Having thus described my invention, what I claim as new and desire to secure by Letters Patent, is:—

1. A vacuum can, comprising a can body, a cover therefor, adapted to be hermetically 15 secured to the can body, said cover being formed of black steel and having a resisting coating on its inner face, said cover having a portion of the outer or oxidized surface thereof removed, and having solder secured thereto, said solder and cover having a perforation formed therethrough, through 20 which the can may be placed under vacuum.

2. A vacuum can, comprising a can body, a cover therefor, adapted to be hermetically 25 secured to the can body, said can body and cover being formed of black steel, and having a resisting coating on the inner face thereof, said cover having a depression

formed centrally therein, the outer or oxidized surface of said depressed portion of 30 the cover being removed and having solder secured thereto, said solder and cover having a perforation extending therethrough, through which the can may be placed under 35 vacuum.

3. A vacuum can comprising a can body, and a cover therefor adapted to be hermetically secured to the can body, said can body and cover being formed of black steel and having a coating of lacquer on the inner 40 face thereof, said cover having a depression formed centrally therein, the outer or oxidized surface of said depressed portion of the cover being removed and having solder 45 secured thereto, said solder and cover having a perforation extending therethrough through which the can may be placed under vacuum, said can body and cover having a coating of varnish on its outer face to prevent the black steel from oxidizing. 50

In testimony whereof I affix my signature in the presence of two witnesses.

EDWIN NORTON.
